UNITED STATES PATENT OFFICE.

HOMER C. HILL AND SAMUEL SEE MIDDLETON, OF CLINTON, ILLINOIS.

DESIGN FOR A CARPET-STRETCHER.

SPECIFICATION forming part of Design No. 26,881, dated April 13, 1897.

Application filed February 17, 1897. Serial No. 623,882. Term of patent 7 years.

To all whom it may concern:

Be it known that we, HOMER C. HILL and SAMUEL SEE MIDDLETON, citizens of the United States, residing at Clinton, in the 5 county of De Witt and State of Illinois, have invented a new and original Design for a Carpet-Stretcher; and we do hereby declare the following to be a full, clear, and exact description of the invention, such as will enable 10 others skilled in the art to which it appertains to make and use the same.

In the accompanying drawings, which illustrate a carpet-stretcher embodying our design, Figure 1 is an upper perspective view 15 of the article. Fig. 2 is a lower perspective view of the same, and Fig. 3 is a central longitudinal section through the article shown in perspective in Figs. 1 and 2.

Our design consists, essentially, of a carpet-stretcher comprising a head-piece having 20 a convexed upper surface and a sharp forward edge, a pair of curved legs extending rearwardly from the opposite ends of the said head-piece, said legs being similar and first 25 converging and then diverging and terminating in downwardly-curved and sharpened

points, and a cross-piece connecting said legs at or about the point where they approach each other the nearest, as shown in the accompanying drawings, wherein—

30

A represents the head-piece having convexed upper surface a^2 and sharpened forward edge a .

A' A' represent the curved legs having converging portions A^3 A^3 and downwardly- 35 curved and sharpened points a' a' , and A^2 represents the cross-piece connecting the said two legs at their nearest point.

In Figs. 2 and 3 the under face of the head-piece is shown as concaved at a^0 , but this is 40 not essential to the design.

What we claim is—

The design for a carpet-stretcher, substantially as herein shown and described.

In testimony whereof we affix our signatures in presence of two witnesses. 45

HOMER C. HILL.

SAMUEL SEE MIDDLETON.
